UNITED STATES PATENT OFFICE.

WALTER J. BARRON, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,017,844.

Specification of Letters Patent.

Patented Feb. 20, 1912.

Application filed January 26, 1911. Serial No. 604,780.

To all whom it may concern:

Be it known that I, WALTER J. BARRON, citizen of the United States, and resident of the borough of Brooklyn, city of New York, in the county of Kings and State of New York, have invented certain new and useful Improvements in Type-Writing Machines, of which the following is a specification.

10 My invention relates to ribbon mechanism for type-writing machines and its general object is to provide improved mechanism of the character specified.

More specifically one object of the invention is to provide improved means for enabling the ribbon to be used throughout substantially its entire width in that class of machines wherein the ribbon is vibrated at the printing operation and more especially 20 in machines which employ a shiftable platen.

Another object is to provide means for enabling predetermined widthwise portions of the ribbon to be employed at will in machines of the character referred to, thus providing for the use of a two-color ribbon or one having a plurality of widthwise fields differing in character.

To the above and other ends my invention 30 consists in the features of construction, combinations of devices and arrangements of parts hereinafter described and particularly pointed out in the claims.

In the present embodiment of my invention I provide a vibrator which is formed with a slot, the upper edge of which is stepped, thus enabling the vibrator to be taken up at different points by the operating lever in the course of its movement.

40 Said operating lever is pivoted to vibrate toward and from the printing point and is also pivoted to swing widthwise of the direction of its vibratory movement, the swinging movement being controlled by 45 hand operated means and enabling the operating lever to be normally positioned on opposite one or another of the steps on the vibrator. Both the vibrator and the operating lever which engages with it are supported on fixed parts of the machine but 50 their actuating or vibrating devices are shifted automatically, when the platen is shifted to change case, by novel devices which are operated by the platen shifting 55 frame.

My invention will be more specifically described in connection with the accompanying drawings wherein—

Figure 1 is a vertical transverse sectional view of a No. 10 Remington typewriting machine embodying my invention, parts of the machine being omitted and parts being broken away. Fig. 2 is a front view, partly in section, of said machine. Fig. 3 is a vertical front to rear sectional view showing the platen carriage and its support, together with parts of the ribbon mechanism in different relations from those in which they appear in Fig. 1. Fig. 4 is a perspective view showing the shifting lever aforesaid detached. Fig. 5 is a perspective view of the hand controlled means for swinging the operating lever. Fig. 6 is front view in vertical section of the mounting of the operating lever. Fig. 7 is a face view of part 75 of a ribbon, showing the courses or paths followed by the types.

As appears from Figs. 1 and 2, the main frame of the machine comprises a base 1, posts 2 and a top plate 3. Above the top plate are fixed trackways 4 cooperating through anti-friction rolls 5 with a truck 6 connected by links 7 to a platen frame 8, which carries a rotary platen 9. A roller 10 mounted on the platen frame runs on a shift rail 11 mounted on uprights 12 connected by a cross rod or bar 13 from the ends of which depend arms 14 pivotally connected at their lower ends with shift key levers 15, which when operated, raise the shift frame and shift the platen frame and platen on the truck 6 to change case. The truck and platen frame together constitute a carriage which is urged leftward by a spring drum (not shown), the leftward step-by-step movements of the carriage being controlled by feeding devices which comprise a rack 16 on the carriage and meshes with a pinion 17 operatively connected with a toothed escapement wheel 18 with which co-operate feed dogs 19 and 20 mounted at the top of a pivoted dog rocker 21. The dog rocker is connected by a link 22 with an arm 23 fixed to a rock shaft 24, said rock shaft having crank arms 25 connected by links 26 to a universal bar 27 underlying a set of key levers 28. Each key lever is connected by a link 29, lever 30 and second link 31 with a type bar 32 pivoted on a hanger 33 secured at the front of a sta- 110

tionary segment 34. The type bars are circularly arranged and are adapted to coöperate with the front face of the platen.

Ribbon spools 35, (shown in Figs. 1 and 2) are vertically disposed, one at each side of the machine, forward of the platen and below the top plate. Each ribbon spool is supported on a horizontal shaft 36 which carries at its rear end a beveled gear 37 adapted to mesh with a beveled gear 38 on a driving shaft 39, which is connected with the spring drum in a known manner so as to receive movements therefrom, and is shiftable endwise so as to connect in alternation with the ribbon spools and feed the ribbon longitudinally back and forth.

The parts heretofore described are common to the No. 10 Remington machine with which I have preferred to show my invention as associated, although it is to be understood that various features of invention may be employed in connection with other forms of writing machines.

The ribbon 40, which in the present case is divided into longitudinal fields *a* and *b* of different characteristics or colors, is guided from the spools over guides 41 and directed inward and rearward toward the printing face of the platen, being threaded through slots in a vibratory ribbon carrier or vibrator which comprises upright parallel arms 42 connected at their lower ends by a plate-like body portion 43 which is offset rearward, as indicated at 43^a, and extends downward behind the type bar segment 34, providing a stem 43^b. The stem 43^b has two vertical guide slots 44 which coöperate with headed guide screws 45 secured in the rear face of the segment 34. A coiled spring 46 connects the off-set portion 43^a with the segment 34 and tends constantly to pull the vibrator downward, normally maintaining the closed upper ends of the slots 44 in contact with the guiding portion of the ribbon below the printing point.

Just below the off-set 43^a the stem 43^b is formed with the slot 47, the lower edge of which is horizontal, the upper edge being cut to provide a plurality of engaging devices or steps numbered respectively 48, 49, 50, 51 and 52. The slot 47 receives the forward end portion of an operating lever 53 fulcrumed at 54 on a rotary member, device or sleeve 55 which bears on a headed shouldered screw 56 that screws up into a lug 3^a on the top plate 3. The mounting of the operating lever is best shown in Fig. 6. It will be understood that said operating lever may swing up or down in a vertical plane about the pivotal center 55 and may also swing laterally or transversely of the vertical plane about the axis of the screw or fixed bearing 56 as a center. The rear arm of the operating lever is constantly

urged upward by a coiled spring 57 which is anchored to a pin 58 on the top plate and normally maintains the forward end portion of the operating lever in contact with the bottom horizontal edge of the slot 47. The upper edge 59 of the rear arm of the operating lever is slightly curved and said rear arm terminates in an upright finger or stop 60.

Coöoperative with the edge 59 is a roller 61 which is pivoted on the forked upper end portion 62^a of an actuating link 62, the lower end whereof is pivotally connected to the arm 23. The bifurcations 62^a embrace the rear arm of the operating lever 53 and maintain the actuating roller 61 in engagement with the upper edge 59. The stop 60 prevents accidental disconnection of the roller 61 from the operating lever.

The actuating link is adapted to be moved forward and backward toward and away from the fulcrum 54 of the operating lever by devices which operate automatically when the platen is shifted so as to increase the throw of the vibrator when the platen is in upper case position and lessen the throw when the platen is restored to lower case position. Said devices comprise a swinging lever 63 shown detached in Fig. 4. Said swinging lever, as appears from Figs. 1 and 3, is pivoted at 64 to the sleeve 55 below the fulcrum of the operating lever. The lower end of the swinging lever is provided with a rearward offset 65 formed with a slot 66 through which the actuating link 62 passes. The upper arm of the swinging lever is provided with a forwardly curved nose 67. Adapted to coöperate with said nose is a cam edge 68 which forms the rearward termination of an arm 69 fast on the shift rod 13. In lower case position the cam 68 coöperates with the nose 67 to maintain the swinging lever, as in Fig. 1, thus locating the link 62 in its rearmost position, the roller 61 being farthest from the fulcrum 54 so that the least extent of movement will be communicated to the operating lever at printing operation.

When, however, the platen is shifted upward as in Fig. 3, the cam 68 cams the nose 67 rearward, swinging the lower arm of the lever 63 forward and correspondingly swinging the link 62 so that the roller 61 will operate nearer the fulcrum 64 and communicate a greater extent of throw to the operating lever so as to compensate for the increased throw necessary to elevate the ribbon to cover the printing point on the shifted platen. As stated, the edge 59 has a slight curvature. The center of the curve is co-axial with the center about which the link 62 swings so that the forward and backward movements of the roller 61 along its track 59 will not affect the operating lever.

It will be understood that at printing op-

erations the printing keys act through the universal bar 27 to rock the shaft 24, thus actuating the arm 23 and correspondingly lowering and raising the actuating link 5 which vibrates the operating lever, causing the forward arm of the same to rise and pick up the ribbon vibrator so as to elevate the same and present the ribbon to the printing point on the platen. The point at which 10 the vibrator will be picked up will depend on the step on the vibrator which the operating lever underlies. For example, when the operating lever underlies the step 48, it will be closely connected with the vibrator 15 and the latter will start to move when the operating lever starts; while if the operating lever underlies the step 51 the operating lever will move a considerable distance before it acts on the vibrator. Thus it will be 20 seen that by locating the operating lever under one or another of the steps the extent of throw communicated to the vibrator and the ribbon will be varied at will. In order to so locate the operating lever I provide 25 devices which coöperate with said lever to swing it transversely of the vibrator on the bearing screw 56. Said devices, as best appears from Figs. 2 and 5, comprise a slide bar 70 which terminates at its inner end in 30 an upright portion 71 formed with an open vertical slot 72 which receives and controls the forward end portion of the operating lever 53. The left-hand portion of the slide bar 70 is guided on a fixed bracket 73 and the right-hand end of said slide bar is pivotally connected at 74 with an upright crank arm 75 which is pivoted at the rear end of a rock shaft 76, the latter bearing in a fixed lug 77 and extending forward and through 40 the right-hand front corner post 2, terminating in a knurled finger button or key 78. Forward of the corner post the rock shaft 76 is provided with an upright pointer 79 which coöperates with indicating marks 80, 45 81 and 82 formed on an indicating plate 83 secured to the corner post. A swinging stop 84 is adapted to co-act with the pointer to limit the leftward turning movements of the rock shaft and connected parts but said 50 stop may be swung upward and out of operation so as to permit said pointer to co-act with a fixed stop or forwardly extending stud 85, the stud 85 permitting further leftward movement of the pointer and rock 55 shaft than does the movable stop 84. It will be observed that the pointer has the double functions of an indicator and a stop device. The upper edge of the slide bar 70 is provided with a series of notches 86 60 which are engageable by the free end of a spring detent 87 secured at 88 to the frame of the machine. By turning the key or button 78 the rock shaft may be rocked to and fro, sliding the bar 70 in and out and swinging the operating lever laterally so as to lo-

cate it beneath one or another of the steps on the vibrator. There are four operating steps on the vibrator and an additional step 52 which is so located that it will never be reached by the operating lever during its swing and so will provide for allowing the vibrator to remain quiescent during printing operations when it is desired to operate the typewriter for stencil or mimeograph work. The coöperating detent devices 87 and 86 70 will maintain the slide bar and connected parts in set or predetermined positions so that the slotted guide 71 may be set at will to confine the operating lever between the walls of the guide slot 72 to predetermined 75 paths of up and down vibration. As stated, there are four steps on the vibrator with which the operating lever co-acts to lift the vibrator and ribbon. When the lever co-acts with the step 51 the lost motion will be 80 greatest and the vibrator will be elevated to its least extent so that the types will follow a path *w* (Fig. 7) along the upper portion of the ribbon field *a*. When, as shown in Fig. 2, the operating lever is located beneath the step 50 the vibrator and ribbon will be elevated to a slightly greater extent and so as to cause the types to print along the lower portion of the printing field *a* in 85 the path represented by the dotted line in 90 Fig. 7. Correspondingly, when the operating lever is located opposite the steps 49 and 48 the vibrator and ribbon will be elevated so as to present respectively the upper and lower portions of the printing field *b* 95 to the types and cause said types to follow the paths indicated by the dotted lines *y* and *z* in Fig. 7. Thus it will be seen that I provide for making use of the ribbon in four 100 parallel paths, thus thoroughly exhausting 105 the printing surface.

Each of the color indicating marks corresponds to two set positions of the operating lever. When the operating lever is operated under the step 51 the pointer 79 will be in contact with the stop 84 so that ordinarily it will not be possible to throw the operating lever out of operative relationship with the vibrator. When it is desired to render the operating lever inoperative, as for mimeographing purposes or the like, the stop 84 is thrown out and the finger key 78 turned to bring the pointer or stop 79 into engagement with the stop 85, thus moving the connected parts so as to reset the operating lever under the step 52. In the opposite direction or toward the right the movements of the hand operated parts are limited by a stop 89 with which the pointer 79 is adapted to contact. 110

It will be observed that by my present 115 invention I provide a vibrator which has a single normal position but which is adapted to be vibrated or thrown a plurality of different extents for both the lower and upper 120 case positions of the shiftable platen by 125 130

improved devices which comprise an operating lever having a double movement, one a vibratory movement and the other movement transverse of the vibratory movement, the transverse movement changing the normal relationship between the operating lever and the vibrator so that the throw of the lever may be varied. The operating lever is shiftable to vary the throw of the vibrator and the actuating link is shiftable to vary the throw of the operating lever. In other words, there is an element *i. e.*, the operating lever, which is shiftable to vary the ribbon throw and which in turn is actuated by devices which are themselves shiftable to vary the throw. My invention provides improved and simplified means for obtaining a comparatively large number, four in the present case, of paths of use widthwise of the ribbon so as to thoroughly exhaust the ink therefrom.

Various changes may be made without departing from my invention.

What I claim as new and desire to secure 25 by Letters Patent, is:—

1. In a typewriting machine, the combination of a platen, shifting means therefor, a ribbon vibrator, means for vibrating the same including a link, and varying means operative on said link independently of said vibrator to vary the action of the vibrating means when the platen is shifted, said varying means comprising a cam having an unvarying relationship with said shifting 35 means.

2. In a typewriting machine, the combination of a platen, a key controlled shift frame, a ribbon vibrator, means for vibrating the same including a link, and a cam fixed to the 40 shift frame and operative on said link independently of said vibrator to vary the action of the vibrating means.

3. In a typewriting machine, the combination of a platen; platen shifting means; a 45 cam thereon; a ribbon vibrator; means for vibrating the same including a link; and a lever controlling the normal position of said link and operative by said cam.

4. In a typewriting machine, the combination of a ribbon vibrator and actuating 50 means therefor comprising an operating lever, said operating lever being fulcrumed to swing in two directions one of which is transverse of the other.

5. In a typewriting machine, the combination of a ribbon vibrator, an operating lever pivoted to swing in two directions, means for vibrating said lever to throw the vibrator to the printing point, and means for 60 pivotally swinging said lever transversely of its plane of vibration to vary the extent of throw communicated to the vibrator.

6. In a typewriting machine, the combination of a ribbon vibrator, an operating lever, 65 a rotary device on which said operating

lever is fulcrumed, means for vibrating said lever on its fulcrum, and separate means for turning said rotary device.

7. In a typewriting machine, the combination of a ribbon vibrator, an operating lever, 70 a rotary device on which said operating lever is fulcrumed, printing keys operative to vibrate said operating lever at printing operation independently of said rotary device, and separate key controlled means for 75 turning said rotary device to vary the normal position of said operating lever.

8. In a typewriting machine, the combination of a platen, a ribbon vibrator, an operating lever, a rotary device to which said 80 lever is fulcrumed, actuating devices for said operating lever, platen shifting means, connections between said platen shifting means and certain of said actuating devices, and means for turning said rotary device 85 at will to alter the normal position of said operating lever.

9. In a typewriting machine, the combination of a platen, a ribbon vibrator, an operating lever, a rotary device to which said 90 lever is fulcrumed, actuating devices for said operating lever, platen shifting means, connections between said platen shifting means and certain of said actuating devices, and means for turning said rotary device at 95 will to alter the normal position of said operating lever, certain of said connections being supported on said rotary device.

10. In a typewriting machine, the combination of a platen, a ribbon vibrator, means 100 for retaining said vibrator in a single normal position, an operating lever, key controlled means for varying the normal position of said operating lever to vary its connection with said vibrator, and means 105 for actuating said operating lever at printing operation.

11. In a typewriting machine, the combination of a platen, a ribbon vibrator, means for detaining said vibrator in a single normal position, means for communicating rotary movements to said operating lever to vary its position and point of connection widthwise of the vibrator, and separate means for actuating said operating lever at 115 printing operation.

12. In a typewriting machine, the combination of a platen, a vibrator having a single normal position and provided with a plurality of engaging devices, an operating lever pivoted to swing widthwise of said vibrator to engage at will with predetermined ones of said engaging devices, and means for actuating said operating lever at printing operation.

13. In a typewriting machine, the combination of a platen, an upright ribbon vibrator provided with a series of steps, a spring retaining said vibrator in normal position, an operating lever, a spring for re- 130

5 training said operating lever normally engaged with the bottom of said slot, means for moving said operating lever to underlie any predetermined step, and means for actuating said operating lever.

14. In a typewriting machine, the combination of a platen, an upright ribbon vibrator provided with a step, a slot having a series of steps along its upper edge, a spring retaining said vibrator in normal position, an operating lever, a spring for retaining said operating lever normally engaged with the bottom of said slot, a rotary sleeve to which said operating lever is fulcrumed, key controlled means for setting said sleeve to locate said operating lever under predetermined steps, indicating devices coöperating with said last named means, and means for actuating said operating lever at printing operation.

15. In a typewriting machine, the combination of a vibrator, actuating devices therefor and combined detent and stop devices for certain of said actuating devices comprising a fixed stop and a movable stop normally preventing some fixed stop from being used.

16. In a typewriting machine, the combination of a vibrator, a train of actuating devices comprising an element engageable with the operating lever and a second element engaging with the first element, means for shifting the first element to vary its effect on the operating lever, and means for shifting the second element to vary its effect on the first element.

17. In a typewriting machine, the combination of a vibrator, an operating lever, a key controlled actuating device for the op-

erating lever, means for varying the normal position of the operating lever to change the extent of throw imparted to the vibrator, and means for varying the normal position of the actuating device to change the extent of movement imparted to the operating lever.

18. In a typewriting machine, the combination of a platen, platen shifting devices, a vibrator, an operating lever, a key controlled actuating device for the operating lever, means for varying the normal position of the operating lever to change the extent of throw imparted to the vibrator, and means for varying the normal position of the actuating device to change the extent of movement imparted to the operating lever, said last recited means being automatically operated by said platen shifting devices.

19. In a typewriting machine, the combination of a vibrator having a plurality of steps, and an operating lever shiftable to underlie said steps, one of said steps being above the point to which the lever may be actuated.

20. In a typewriting machine, the combination of a vibrator having a plurality of steps, two for each printing field of the ribbon, and an operating lever shiftable to engage predetermined steps.

Signed at the borough of Manhattan, city of New York, in the county of New York and State of New York, this 25th day of January, A. D. 1911.

WALTER J. BARRON.
